UNITED STATES PATENT OFFICE

1,997,621

CENTRIFUGAL DRIER

Charles G. Adsit, Des Moines, and George W. Lewis, Grinnell, Iowa, assignors to Grinnell Washing Machine Corporation, Grinnell, Iowa, a corporation of Iowa

Application March 24, 1932, Serial No. 600,899

5 Claims. (Cl. 210—75)

Our improved clothes drier may be used to advantage as an attachment for a domestic washing machine.

One of our objects is to provide a machine of the centrifugal extractor type in which, when the cover of the clothes container is opened, even to a slight degree, the rotation of the clothes container is instantly and automatically stopped to thereby avoid injury to the operator or the machine.

Another object is to provide a stationary drain and work table at the top of the drier for the convenience of the operator, and so constructed as to drain water into the clothes drier through an opening in the center of the table; and also in this connection to provide an adjustable drain spout below the table for delivering water from the extractor in any desired direction.

A further object is to provide a clothes drier of the class in which a current of air is automatically forced downwardly through the center of the clothes container, then outwardly through the clothes to a point of discharge to thereby dry the clothes to a greater degree than can be done by the centrifugal action only.

Our invention consists in the construction, arrangement and combination of the various parts of the device, whereby the objects contemplated are attained, as hereinafter more fully set forth, pointed out in our claims, and illustrated in the accompanying drawings, in which:

Figure 1 shows a vertical, central, sectional view illustrating our invention and showing a portion of the washing machine tub upon which it is supported.

Figure 2 shows a side elevation of a washing machine tub and our improved centrifugal drier applied thereto.

Figure 3 shows a top or plan view of a washing machine with our improved centrifugal drier applied thereto and illustrating two other tubs located adjacent thereto and in position to have the water from the water discharge spout flow either into the washing machine or into either of said tubs, the position of the spout being indicated by dotted lines adjacent to the two tubs.

Figure 4 shows a vertical, central, sectional view of our improved clothes drier with the cover shown in a slightly elevated position and by dotted lines in fully open position, and the clothes container raised and tilted slightly to one side against the friction device for stopping its rotation.

Figure 5 shows an inverted plan view illustrating

the detachable flange at the top of the clothes container.

Figure 6 shows a sectional view on the line 6—6 of Figure 5, and being also an inverted position.

Figure 7 shows a sectional view on the line 7—7 of Figure 1.

Figure 8 shows a sectional view on the line 8—8 of Figure 7.

Figure 9 shows an enlarged detail sectional view on the line 9—9 of Figure 1.

Referring to the accompanying drawings, we have used the reference numeral 10 to indicate generally the washing machine body to which my improved clothes drier is attached. The clothes drier comprises a cylindrical casing 11 open at its top and having a bottom 12 provided with a ball bearing device 13 for the drive shaft 14. This drive shaft has on its lower end a beveled friction wheel 15 to frictionally engage a drive friction wheel 16. The shaft and bearing are so arranged that the shaft may slide upwardly and downwardly on the bearing and may tilt laterally to a slight extent for purposes hereinafter made clear.

At the top of the casing 11 there is a stationary trough 17 with an outer vertical wall 18 projected upwardly above the top of the casing and fixed to a circular combined drain and work table 19, which has an upwardly extended flange 20 at its periphery. The bottom of the table preferably inclines downwardly and inwardly toward the center thereof.

The center of the work table is open and a hinged cover member 21 is mounted therein. At the side of this cover member opposite from the hinge is a latch 22 for locking the cover in closed position. In the bottom of the trough 17 is a series of openings 23, and these openings are preferably inclined as shown in detail in Figure 9, in the same direction as the path of rotation of the clothes container, they being extended downwardly and forwardly relative to said path.

Mounted on the outer surface of the casing 11 below the stationary trough 17 is a circular trough 24 supported on the blocks 25 on the exterior of the casing 11, so that this trough 24 may be rotated about the casing, and this trough has at one side a discharge spout 26.

By means of the mechanism just described it is obvious that water thrown outwardly from the upper end of the casing will be collected in the trough 17 and will then drip into the trough 24 and may be discharged through the spout 26 in any direction. In Figure 3 the spout is shown as discharging back into the washing machine and by dotted lines its position is shown as being able

to discharge into either of the two tubs 27 and 28.

In this connection attention is called to the fact that by means of this construction a very useful and advantageous combined table and drain board is formed, and without in any way interfering with any of the ordinary functions of a centrifugal drier of this character.

Clothes may be placed on the table either before or after going through the extractor, and if any water should drain from them, it will all go back into the extractor, and this improved table differs from the drain board devices now in general use in which the water discharged from the clothes drier flows over the drain board to a point of discharge, whereas with our improvement none of this water discharged from the extractor gets to the table.

Fixed to the shaft 14 is a clothes container 29 of the ordinary construction and provided with an outwardly extended flange 30 at its upper end. At the central portion of the container we have provided a perforated tube 31 open at its top for forming a downward passageway for air which may then move outwardly through the clothes and upwardly to a point of discharge.

Mounted on top of the clothes container is a circular flange 32 fixed to the container by bolts 33. This flange, as is clearly shown in the inverted plan view in Figure 5, is provided with a series of grooves 34, which grooves are inclined rearwardly and outwardly relative to the path of movement of the flange, as indicated by the arrow in Figure 5. These grooves, as will be seen on reference to Figure 1, form a passageway to conduct air outwardly between the flanges 30 and 32, and by having them inclined as shown in Figure 5, one wall of the groove functions as an impeller blade to force air outwardly when the clothes container is being rapidly rotated.

In the operation of this part of the device, and assuming that the clothes container is filled with wet clothes, then during the first part of the operation, the water is extracted from the clothes by centrifugal action and moves upwardly and outwardly through the grooves 34. When this has proceeded to a certain extent, a certain amount of water is held in the clothes by capillary action and cannot be removed by the centrifugal action of this machine. In some instances it is very desirable to dry the clothes to a greater extent than can be done by the centrifugal action alone.

With our improvement a continued rotation of the clothes container will cause air to be forced outwardly through the grooves 34 both by centrifugal action and the impeller-blade-like action of the grooves 34, and this will cause air to be drawn into the upper part of the perforated tube 31 and downwardly in said tube and then outwardly through the clothes and upwardly to a point of discharge, and we have found in actual practice that clothes may be dried within a reasonable time to a point where they are ready for ironing.

Mounted upon the under side of the hinged cover 21 is a ball bearing device indicated generally by the numeral 35, and a centering cover 36 is rotatably supported by said ball bearing device on the under side of the hinged cover 21. The lower surface of the centering cover 36 is inclined downwardly and toward the center, as shown in Fig. 1, and coacts with the flange 32 so that as the centering cover is moved downwardly, it will tilt the upper end of the clothes container and the flange 32 in the direction re-

quired for centering the clothes container within the casing and the cover 36 will rotate with the clothes container.

On the inner surface of the casing is provided a series of friction devices preferably in the form of a rubber block 37. These friction devices are positioned slightly spaced apart from the exterior of the clothes container 29 when centered. When the cover 36 is removed from its contact with the flange 32, then the clothes container will tilt laterally far enough to engage one or more of these friction blocks.

With this part of the device, and in actual practice we have demonstrated that when the clothes container is running at its maximum, say for instance one thousand revolutions per minute, and then the centering cover 36 should be suddenly elevated, the upper end of the clothes container will tilt laterally into engagement with said friction blocks, and this will cause the rotation thereof to be stopped almost instantly.

In addition to this we have provided a spring 38 pressed upwardly against the lower end of the clothes container, and so arranged that when the cover 36 is elevated, the shaft 14 will be slightly elevated, and this will move the friction wheel 15 on the lower end of the shaft out of driving contact with the coacting friction wheel 16, so that the container is instantly and automatically stopped in its rotation when the centering cover 36 is elevated, and is then automatically retained out of driving contact with the driving friction wheel. This we have found to be of great benefit in avoiding accidents both to operators and to the machine itself, and no objectionable results follow if the cover is raised at the time the clothes container is rotating at normal speed.

We claim as our invention:

1. In a device of the class described, the combination of a rotary clothes container having means for discharging water outwardly from its upper end, a casing in which the clothes container is supported, an annular trough device fixed to the top of the casing and shaped to receive water discharged from the clothes container and having an opening in its bottom portion, a work table and cover supported by said trough device, and a second annular trough having a discharge spout and movably mounted below the first trough device to rotate concentrically of the first trough and to receive water therefrom.

2. In a machine of the class described, a clothes container, a drive shaft fixed to its lower end, a support for the shaft shaped to permit it to move lengthwise and to tilt laterally, a friction drive wheel fixed to the lower end of the shaft, a spring for moving the container upwardly, a cover, means for holding the cover in position with the container moved downwardly against the pressure of said spring, said parts being so arranged that when the cover is raised, the spring will raise the friction drive wheel, and stationary friction devices adjacent to the outer surface of the container and in position to be engaged by the container when the container is tilted to thereby stop its rotation.

3. In a device of the class described, the combination of a rotary clothes container having means for discharging water outwardly from its upper end, a casing in which the clothes container is supported, an annular trough fixed to the top end of the casing and spaced a slight distance from the outer walls of said casing and shaped

- to receive water discharged from the clothes container and having a series of inclined openings in its bottom, a second annular trough supported below the first annular trough having its side walls overlapping the side walls of the first annular trough, means for mounting said second trough to permit it to move concentrically of the first trough, and a discharge spout carried by the first annular trough.
- 5 4. In a device of the class described, a vertical casing, an annular trough carried by the upper end of said casing having discharge openings in its bottom, a second annular trough rotatively mounted about said casing and beneath the first trough, and a discharge spout for said second annular trough.
- 10 5. In a device of the class described, a vertical casing, an annular trough carried by the upper end of said casing having discharge openings in its bottom, a second annular trough rotatively mounted about said casing and beneath the first trough, a discharge spout for said second annular trough, a table carried by the first trough having a central opening, the bottom of said table being inclined downwardly and inwardly and having its outer edge provided with an upwardly extending flange, said table being considerably larger in diameter than said casing.
